CIRCUIT BREAKER OF FLUID IMMERSED TYPE
HAVING PAIR OF SERIES CONNECTED INTERRUPTERSKazuo Henry Date, South Milwaukee, Wis., assignor to
McGraw-Edison Company, Milwaukee, Wis., a corporation of DelawareFiled Nov. 15, 1962, Ser. No. 237,985
13 Claims. (Cl. 200—150)

This invention relates to circuit interrupting devices and more particularly to circuit interrupting devices of the liquid immersed type.

In the interruption of a capacitive load, large transient over-voltages are sometimes produced. During the switching of such capacitive loads the current is initially interrupted at the first current zero with relatively little difficulty because the load remains at approximately the crest value of the instantaneous voltage of the source for a short time during which there is relatively little voltage across the circuit breaker interrupting contacts. However, one-half cycle after the first current zero, the voltage of the source is reversed to its crest value so that a voltage of approximately double the crest value appears across the circuit breaker contacts as a recovery voltage. During this time the arc is likely to restrike across the partially separated circuit breaker contacts. Restrikes of this nature, being of an oscillatory character, may produce serious high over-voltages in the system.

An object of the invention is to provide a circuit interrupting device capable of interrupting capacitive currents as well as normal load currents.

It is another object of the invention to provide a circuit interrupter for use in capacitive switching in which the buildup of dielectric material between the parted circuit breaker contacts is more rapid than the buildup of voltage thereacross.

A more specific object of the invention is to provide a circuit breaker having a pair of series connected interrupters in which one of the interrupters parts prior to the first current zero for affecting the initial interruption and in which the second interrupter parts subsequent to the first current zero or within a short time thereof so that the second interrupter will provide a substantially ion and other particle free dielectric gap for the prevention of restrike during the relatively high voltage surges which follow.

These and other objects and advantages of the instant invention will become more apparent from the detailed description thereof taken with the accompanying drawings in which:

FIG. 1 is a side elevational view of the interrupter incorporating the instant invention;

FIG. 2 is a side elevational view with parts broken away of a portion of the interrupter shown in FIG. 1;

FIG. 3 is a view taken along lines 3—3 of FIG. 1;

FIG. 4 is a view taken along lines 4—4 of FIG. 1; and

FIG. 5 shows a plot of the contact separation of the device depicted in FIG. 1.

Referring now to the drawings in greater detail, the current interrupter according to the instant invention is shown to be of the low oil type which includes an insulating housing 10 of porcelain or other dielectric material. The housing 10 is supported on a metallic base 11 to which a lead wire (not shown) may be connected. The base 11 is provided with an upstanding flange 12 which defines a socket for surrounding the lower end of the housing 10 and to which it is cemented by a low temperature melting alloy 13. A gasket 17 between the bottom surface of porcelain housing 10 and the metallic base 11 hermetically seals the lower end of housing 10.

A contact operating mechanism enclosure 14 is disposed at the upper end of the housing 10 and has a similar depending flange 15 which is cemented at 16 to the upper end of the housing 10. It will be understood that the enclosure 14 is fluid tight and contains an operating mechanism of any well known type which will cause a movable contact rod 18 to execute substantially straight line axial movement, but only one actuating link 19 thereof is illustrated for the sake of brevity. For a more complete disclosure of such a contact rod operating mechanism, reference is made to Patent No. 2,838,638 to K. H. Date and assigned to the assignee of the instant invention.

The interior cylindrical bore 20 of the insulating housing 10 constitutes a fluid reservoir filled with dielectric fluid 21 to a level indicated by dashed lines 22. A plurality of apertures 23 are provided in the lower end of the housing 14 for the purpose of permitting expansion of dielectric fluid into the housing 14 during current interruption and for facilitating restoration of the normal fluid level by draining fluid back into the interior of housing 10 when the circuit interrupter is inactive.

The contact rod 18 is shown to comprise an upper conductive section 30, a lower conductive section 31 and an intermediate non-conductive section 32, which joins the conductive sections 30 and 31. The conductive sections 30 and 31 may be composed of aluminum for lightness and for this reason has a tip 33 of arc resistant material such as copper tungsten. The non-conductive portion 32 may be of epoxy resin.

A pair of insulating tubes 34 and 34' surround the contact rod 18 and are affixed in a coaxial endwise relation by a pair of channel members 37, a conductive stud 38 and a bolt 39. The upper tube 34 has a pair of opposed cutaway portions 35 intermediate its ends to expose the upper conductive portion 30 of the contact rod to the dielectric fluid 21 within the housing 10. An arc interrupting chamber 36 is disposed intermediate the ends of the lower tube 34' and surrounds the lower conductive portion 31 of the contact rod 18. The conductive stud 38, which is positioned intermediate the cutaways 35 and the interrupting structure 36, performs the function of supporting contact assemblies 40 and 42 which bridge the non-conductive portion 31 of the contact rod 18 when the latter is in a closed position and also provide a current path between these contact assemblies.

A stationary wiping contact assembly 44 is disposed below the metallic housing 14 and in the upper end of the tube 34 for slidably engaging the upper conductive portion 30 of the contact rod 18. Mounted on the metallic base 11 and extending upwardly into the lower end of the tube 34 is a stationary contact and dashpot assembly 45 engageable by the lower conductive portion 31 of rod 18.

The contact assembly 44 includes a set of wiping contact fingers 46 pivotally supported on an annularly grooved conductive post 48 which depends from the metallic enclosure 14 and which has an axial bore 47 for slidably receiving the rod 18. The fingers 46 are biased radially toward engagement with the contact rod portion 30 by tensional garter springs 49.

As seen in greater detail in FIG. 2, the contact assembly 42, which slidably engages the lower contact rod conductive portion 31, similarly includes an annularly grooved axially bored conductive post 50 depending from the stud 38 and a plurality of contact fingers 52 biased toward engagement with the contact rod 18 by garter springs 54. A similarly shaped conductive post 55 extends upwardly from the stud 38 and carries a pair of outwardly flared and upwardly extending contact fingers 56 which carry contact members 57 at their upper ends and which

are biased by springs 58 toward engagement with a pair of contact elements 59 which are carried at the outer ends of a transversely extending conductive adapter 60 affixed to the lower end of the contact rod conductive portion 30. It can thus be seen that the point of engagement between the members 57 and the elements 59 is at a point displaced radially from the surface of the contact rod 18. This insures that when the interrupter is opened the arc does not erode the non-conductive portion 32 of the rod 18 upon the separation of the contact rod portion 30 from the contact assembly 40.

The lower contact and dashpot assembly includes a conductive stud 62 affixed to the base plate 11 and having a central bore 63 for receiving a hollow contact post 65. A plurality of contact fingers 66 are pivotally mounted on the contact post 65 and urged into high pressure engagement with the contact rod 18 by springs 68. A piston 70 is reciprocally received within the post 65 and is urged upwardly by a coil spring 72 into engagement with an overhanging stop 73 formed by the tips 74 of contact fingers 66. A check valve consisting of a ball 76, a seat 77 and an aperture 78 is disposed in the lower end of the post 65. In addition, an aperture 80 is formed in the stud 62 to place the bore 63 in communication with the dielectric fluid 21 in the insulating housing 10.

It will be appreciated that when the movable contact rod 18 moves into its closed position it will impact the piston 70 which absorbs the kinetic energy from the contact rod 18. This energy forces the piston 70 to move downward slightly as a portion of the dielectric fluid trapped below it leaks along its sides. The spring 72 then returns the piston 70 to its initial position as more fluid is drawn through the apertures 70 and 78 and past the ball check 76. In addition, it will be appreciated that because of the position of the aperture 80 in the stud 62 and of the aperture 78 in the lower end of the post 65 no sludge or small metal particles will be drawn below the piston 70.

The details of the arc interrupting chamber 36 forms no part of the instant invention. It will suffice for the purposes of the present disclosure to note that chamber 36 consists of a plurality of plates 82 of an insulating material which are joined in a stacked relation in any convenient well known manner and each of which has a central aperture 83 (see FIG. 4) for receiving the contact rod 18. Each of the plates 82 also has a plurality of fluid duct apertures 84 which intersect and are spaced circumferentially around the central aperture 83. It can be seen, therefore, that the apertures 83 of the plates 82 cooperate to form a continuous central bore 85 through the chamber 36 and the apertures 84 form continuous fluid ducts 86 which surround and open into the bore 85. A plate 87 having a single aperture is disposed at the upper end of the chamber 36 for closing the upper end of the ducts 86. While the ducts 86 are shown to be straight it will be understood that the discs 82 may be so arranged that they present other types of paths such as a spiral. The tube 34' is provided with a pair of apertures 88 adjacent the contact assembly 45 for venting the bore 85 and the ducts 86 of chamber 36. For a more complete description of the interrupter 36 and its method of operation, reference is made to U.S. Patent No. 2,886,673 to A. Van Ryan and assigned to the assignee of the instant invention.

It can be seen from FIG. 5 that the overlap of the contact fingers 56 and the contact members 59 is substantially greater than that of the contact rod portion 31 and the contact fingers 66. For example FIG. 5 shows the plot of contact travel against elapsed time in cycles for one particular embodiment of the invention. Here it can be seen that the contact rod 18 will have moved upwardly approximately $\frac{3}{4}$ " after the parting of the lower contacts 31-66 before the upper contacts 56-59 part. This difference in overlap is designed, taking into con-

sideration the acceleration of the contact rod, so that the contact members 59 will remain in engagement with the contact fingers 56 until approximately one half cycle after the separation of the rod portion 31 from the contact fingers 66. This will insure that the upper contacts 56-59 will part either subsequent to or immediately before the current goes through its first zero and is interrupted by the lower contacts 31-66. As a result there will either be no arc struck at the upper contacts 56-59 or the arc will be so short in length and duration that little contamination of the oil therearound will result.

The operation of the interrupter according to the invention will now be discussed with reference to FIGS. 1 and 5. During the interruption of a capacitive current, the operating mechanism (not shown) will begin moving the contact rod 18 upwardly. This will disengage the lower contact rod portion 31 from the contact fingers 66 whereby an arc will be drawn therebetween. As the current passes through its first zero the interrupting structure 36 will have little difficulty interrupting the arc. However, as illustrated in FIG. 5, the contact members 59 and the contact fingers 56 will be so proportioned that they will stay in engagement during all or substantially all of this initial movement of the contact rod 18.

After the current passes through its first zero the voltage across the interrupter will build up rapidly. This rapid buildup of voltage would normally cause a restrike of the arc at the lower contacts 31-66 due to the presence of ionized particles and other products of arc interruption existing in this gap as a result of the initial interruption. However, the separation of the upper contacts 56-59 has now occurred to provide a relatively uncontaminated gap in series with the lower contacts 31-66. In addition because the contact rod 18 is now at a steeper portion of the displacement curve of FIG. 5 the uncontaminated gap at the upper contacts 56-59 is lengthening faster than the voltage buildup across the device. As a result there is no restrike across the interrupter.

Thus, it can be seen that even though the initial contact rod movement is insufficient to provide enough contact separation to prevent restrike after the first half cycle during the interruption of a capacitive current, the provision of a second interrupter in series, which remains closed during substantially all of the arcing across the first interrupter, will provide a sufficiently rapid dielectric buildup to prevent such restrike.

While only a single embodiment of the invention has been shown and described, it is intended that the invention be limited only by the scope of the appended claims.

I claim:

1. A circuit interrupter of the fluid immersed type comprising an insulating housing containing a quantity of dielectric fluid, first and second stationary contact means disposed within said housing in spaced apart relation, a contact rod having first and second conductive portions and an intermediate nonconductive portion and being movable longitudinally into and out of a closed position relative to said first and second stationary contact means, said first and second conductive portions being in overlapping engagement with said first and second stationary contact means, respectively, when said contact rod means is in its closed position, said first and second conductive portions and said first and second stationary contact means being operative to provide a series current path when said contact rod means is in its closed position, the degree of overlapping engagement between said second conductive portion and said second stationary contact means being substantially greater than between said first conductive portion and said first stationary contact means so that said second stationary contact means will remain in engagement with said second conductive portion until said first conductive portion has separated a substantial distance from said first stationary contact means.

2. A circuit interrupter of the fluid immersed type

comprising an insulating housing containing a quantity of dielectric fluid, first and second stationary contact means disposed in spaced relation within said housing, an elongate member having first and second conductive portions and an intermediate nonconductive portion and being movable into and out of a closed position relative to said first and second stationary contact means, said first and second conductive portions being in overlapping engagement with said first and second stationary contact means respectively when said elongate members is in its closed position, said first and second conductive portions and said first and second stationary contact means being operative to provide a series current path when said elongate member is in its closed position, an arc extinguishing device disposed adjacent said first stationary contact means and having a passageway in which said elongate member is adapted to reciprocate, the overlapping engagement between said second conductive portion and said second stationary contact means being substantially greater than that between said first conductive portion and said first stationary contact means so that said second conductive portion will remain in electrical engagement with said second stationary contact means until said first conductive portion has separated a substantial distance from said first stationary contact means as said elongate member moves out of its closed position, said second stationary contact means being directly exposed to said dielectric fluid.

3. A circuit interrupter of the fluid immersed type comprising, an elongate insulating housing containing a quantity of dielectric fluid, first and second stationary contact means disposed within said housing in spaced apart relation, a contact rod mounted for longitudinal movement within said housing and comprising a pair of conductive portions and an intermediate non-conductive portion, one of said conductive portions being movable into and out of overlapping engagement with said first stationary contact means, said other conductive portion overlappingly engaging said second stationary contact means, said second stationary contact means bridging said non-conductive portion when said contact rod is in its engaged position to provide a series current path, the overlapping engagement between said other conductive portion and said second stationary contact means being substantially greater than that between said first conductive portion and said first stationary contact means so that said second stationary contact means will remain in engagement with said other conductive portion until said one conductive portion has separated a substantial distance from said first stationary contact means.

4. A circuit interrupter of the fluid immersed type comprising, an insulating housing containing a quantity of dielectric fluid, first and second stationary contact means disposed in spaced relation within said housing, an elongate contact member mounted for longitudinal movement within said housing and having a pair of conductive portions and an intermediate non-conductive portion, each of said conductive portions being movable into and out of overlapping engagement with a different one of said first and second stationary contact means, said second stationary contact means bridging said non-conductive portion when said contact rod is in its engaged position to provide a series current path, an arc extinguishing device disposed adjacent said first stationary contact means and having a passageway in which said elongate contact member is adapted to reciprocate, the overlapping engagement between said second stationary contact means and one conductive portion being substantially greater than that between the other conductive portion and said first stationary contact means so that said second stationary contact means will remain in electrical engagement with said one conductive portion until said other conductive portion has separated a substantial distance from said first stationary contact means, said second stationary contact means being directly exposed to said dielectric fluid.

5. A circuit interrupter of the fluid immersed type comprising an insulating housing containing a quantity of dielectric fluid, first and second stationary contact means disposed in spaced relation within said housing, an elongate member mounted for longitudinal movement into and out of a closed position relative to said first and second stationary contact means and including first and second conductive portions and an intermediate nonconductive portion, said first and second conductive portions being in overlapping engagement with said first and second stationary contact means respectively when said member is in its closed position, said second stationary contact means including contact members spaced radially from the surface of said elongate member, said second 10 conductive portion including radially spaced contact elements for overlapping engagement with said contact members, said first and second conductive portions and said first and second stationary contact means being constructed and arranged to provide a series current path when said elongated member is in its closed position, an arc extinguishing device disposed adjacent said first stationary contact means and having an axial passageway in which said elongate member is adapted to reciprocate, the degree of overlapping engagement between said contact elements and said contact members being substantially greater than between said first conductive portion and said first stationary contact means, so that said second stationary contact means will remain in electrical engagement with said second conductive portion until said first conductive portion has separated a substantial distance from said first stationary contact means.

6. A circuit interrupter of the fluid immersed type comprising an elongate insulating housing containing a quantity of dielectric fluid, first and second stationary contact means disposed in spaced relation within said housing, movable contact rod means comprising a pair of conductive portions and an intermediate nonconductive portion and being movable between open and closed position relative to said first and second stationary contact means, one of said conductive portions slidably engaging said second stationary contact means and the other conductive portion engaging said first stationary contact means when said contact rod means is in its closed position, said second stationary contact means bridging said nonconductive portion when said contact rod means is in its closed position to provide a series current path between said first and second stationary contact means, said one conductive portion and said second stationary contact means remaining in sliding engagement until said contact rod means has moved a substantial distance out of its closed position and after said other conductive portion has moved out of engagement with said first stationary contact means.

7. A circuit interrupter of the fluid immersed type comprising an elongate insulating housing containing a quantity of dielectric fluid, first and second stationary contact means disposed in spaced relation within said housing, a contact rod comprising a pair of conductive portions and intermediate nonconductive portion, said contact rod being movable between open and closed positions relative to said first and second stationary contact means, one of said conductive portions slidably engaging said second stationary contact means and the other conductive portion being in engagement with said first stationary contact means when said contact rod is in its closed position, said second stationary contact means bridging said nonconductive portion when said contact rod is in its closed position to provide a series current path between said first and second stationary contact means, an arc extinguishing device disposed adjacent said first stationary contact means and having an axial passageway in which said contact rod is adapted to reciprocate, said one conductive portion and said second stationary contact means remaining in sliding engagement until said contact rod has moved a substantial dis-

tance out of its closed position and after said other conductive portion has moved out of engagement with said first stationary means, said second stationary contact means being directly exposed to said dielectric fluid.

8. A circuit interrupter of the fluid immersed type comprising an elongate insulating housing containing a dielectric fluid, first and second stationary contact means disposed in spaced relation within said housing, contact rod means comprising a pair of conductive portions and an intermediate nonconductive portion, said contact rod means being movable between open and closed positions relative to said first and second stationary contact means, one of said conductive portions slidably engaging said second stationary contact and the other conductive portion being in engagement with said first stationary contact when said contact rod means is in its closed position, said second stationary contact means bridging said nonconductive portion when said contact rod means is in its closed position to provide a series current path between said first and second stationary contact means, said second stationary contact means including contact members spaced radially from the surface of said contact rod means, said one conductive portion including radially spaced contact elements for slidably engaging said contact members, said contact elements and said contact members remaining in sliding engagement for a substantial distance as said contact rod moves out of its closed position and after said other conductive portion has moved out of engagement with said first stationary contact means.

9. A circuit interrupter of the fluid immersed type comprising, an insulating housing containing a quantity of dielectric fluid, first and second stationary contact means disposed in spaced relation within said housing, a contact rod including first and second conductive portions and an intermediate nonconductive portion and being mounted for longitudinal movement into and out of a closed position relative to said first and second stationary contact means, said first and second conductive portions being in overlapping engagement with said first and second stationary contact means respectively when said contact rod is in its closed position, said second contact means bridging said intermediate nonconductive portion when said contact rod is in its closed position to provide a series current path between said first and second stationary contact means, said second stationary contact means including contact members spaced radially from the surface of said second conductive portion, said contact rod including radially spaced contact elements for overlappingly engaging said contact members, the overlapping engagement between said contact elements and said contact members being substantially greater than that between said contact rod and said first stationary contact means so that said second stationary contact means will remain in electrical engagement with said contact rod until said rod has separated a substantial distance from said first stationary contact means.

10. A circuit interrupter of the fluid immersed type comprising, an elongate insulating housing containing a quantity of dielectric fluid, first and second stationary contact means disposed in spaced relation within said housing, a contact rod mounted for longitudinal movement into and out of a closed position relative to said first and second stationary contact means and having a pair of conductive portions and an intermediate nonconductive portion, one of said conductive portions being in overlapping engagement with said first stationary contact means when said contact rod is in its closed position, said second stationary contact means including contact members spaced radially from the surface of said contact rod, the other of said conductive portions including radially spaced contact elements for overlappingly engaging said contact members when said contact rod is in its closed position, said second stationary contact means bridging said non-conductive portion when said contact

rod is in its engaged position to provide a series current path through said housing, an arc extinguishing device disposed adjacent said first stationary contact means and having an axial passageway in which said contact rod is adapted to reciprocate, the overlapping engagement between said contact elements and said contact members being substantially greater than that between said one conductive portion and said first stationary contact means so that said second stationary contact means will remain in electrical engagement with said contact elements until said one conductive portion has separated a substantial distance from said first stationary contact means, said second stationary contact means being directly exposed to said dielectric fluid.

11. A circuit interrupter of the fluid immersed type comprising, an elongate insulating housing containing a quantity of dielectric fluid, a first stationary contact disposed adjacent one end of said housing, second and third stationary contacts disposed intermediate the ends of said housing and electrically connected to each other, a contact rod mounted for axial movement into and out of a closed position relative to said first and third stationary contacts and comprising a pair of conductive portions and an intermediate non-conductive portion, one of said conductive portions slidably engaging said second stationary contact and being in overlapping engagement with said first stationary contact when said contact rod is in its closed position, said third stationary contact including contact members spaced radially from the surface of said contact rod, the other of said conductive portions including radially spaced contact elements movable into and out of overlapping engagement with said contact members when said contact rod moves into and out of its closed position, said second and third stationary contacts bridging said non-conductive portion when said contact rod is in its engaged position to provide a series current path between said first and second stationary contacts, an arc extinguishing device disposed between said first and second stationary contacts and having an axial passageway in which said contact rod is adapted to axially reciprocate, the overlapping engagement between said contact elements and said contact members being substantially greater than that between said contact rod and said first stationary contact so that said third stationary contact will remain in electrical engagement with said contact rod until said rod has separated a substantial distance from said first stationary contact, said third stationary contact being directly exposed to said dielectric fluid.

12. A circuit interrupter of the fluid immersed type comprising an elongate insulating housing containing a quantity of dielectric fluid, first and second stationary contact means disposed in spaced apart relation within said housing, contact rod means mounted for longitudinal movement between open and closed positions relative to said first and second stationary contact means, said contact rod means including first and second conductive portions and an intermediate nonconductive portion, said first and second conductive portions being movable into and out of engagement with said first and second stationary contact means respectively as said contact rod means moves between its closed and open positions, said second conductive portion and said second stationary contact means being in sliding engagement for a predetermined portion of the movement of said contact rod means out of its closed position and after said first conductive portion has disengaged from said first stationary contact means, said first and second conductive portions and said first and second stationary contact means providing a series current path when said contact rod means is in its closed position.

13. A circuit interrupter of the fluid immersed type comprising an elongate insulating housing containing a quantity of dielectric fluid, first and second stationary contact means disposed in spaced apart relation within

said housing, a contact rod mounted for longitudinal movement between open and closed positions relative to said first and second stationary contact means, said contact rod having first and second spaced conductive portions and an intermediate nonconductive portion, said first and second conductive portions being movable into and out of engagement with said first and second stationary contact means respectively as said contact rod moves between its open and closed positions, said second conductive portion and said second stationary contact means including means for maintaining the electrical engagement therebetween until said first conductive portion has moved a substantial distance out of engagement

5

with said first stationary contact means, said first and second conductive portions and said first and second stationary contact means providing a series current path when said contact rod is in its closed position.
